Inventor:

Bernard R. Dutcher,
By his Atty, J. W. Richards.

UNITED STATES PATENT OFFICE.

BERNARD R. DUTCHER, OF NEW YORK, N. Y., ASSIGNOR TO GRAHAM-CHISHOLM COMPANY, OF NEW YORK, N. Y., A CORPORATION OF NEW YORK.

LOOSE-LEAF BINDER.

Application filed January 21, 1921. Serial No. 438,933.

To all whom it may concern:

Be it known that I, BERNARD R. DUTCHER, a citizen of the United States, residing in New York, in the county of New York and 5 State of New York, have invented certain new and useful Improvements in Loose-Leaf Binders, of which the following is a specification.

This invention relates to improvements in 10 loose-leaf binders and particularly to binding posts cooperating with the loose-leaves and with binder members aiding in their easy manipulation.

My improved posts are especially designed for use with a temporary binder or 15 loose-leaf holder or book similar to that shown in my United States Patent No. 1,403,303, issued Jan. 10, 1922, for binders; but the improvements shown are capable of 20 embodiment and are desirable for use with other forms of temporary binders and in other relations where it is desirable to facilitate the handling of loose sheets.

The main objects of the invention are:

25 First, to provide a loose-leaf binder which facilitates the handling or manipulation of the posts for binding the loose record sheets.

Second, to provide an improved binding post which facilitates the manipulation and 30 handling of temporary binders and the insertion and removal of sheets and prevents the removal of the binding posts therefrom.

Third, to provide a simple, practical, durable easily manufactured binder of the 35 kind mentioned above.

Other objects of the invention will appear as the description proceeds; and while herein minute details of the invention are described, the invention is not limited to these, 40 since many and various changes may be made without departing from the scope of the invention as claimed.

In the accompanying drawing, showing 45 by way of example, one of many possible embodiments of the invention,

Figure 1 is a perspective view of a support with a binder thereon embodying the features of my invention;

Fig. 2 is a fragmental longitudinal vertical sectional view of the binder;

Fig. 3 is a perspective of a detail of the binder; and

Fig. 4 is a face view of the clamp bar of the binder.

My improved binder posts are adapted for 55 use with a loose-leaf book comprising a pack of leaves 5 each having near its inner edge 6 a pair of perforations or holes 7 equally spaced from said inner edge 6, and equally spaced from the adjacent ends 60 of the sheet.

Said book also comprises a pair of hollow binder members 10 and 11 adapted to be placed upon the sides of said pack of leaves near said inner edges and each provided with outer orifices 12 and 13, and inner orifices 14 and 15 registering with each other and with the perforations 7 of the sheets. In the present instance the binder member 10 may be regarded as the locking 70 binder member, and the binder member 11 as the retaining binder member. The diameter of the inner orifice 15 (Fig. 2) is smaller than the diameter of the other orifices 12, 13 and 14 for a purpose which will be 75 explained. Binding or cover boards 18 are hinged to said binder members 10 and 11 and are adapted to cover said pack 5 and project a slight distance at the top and bottom edges of said leaves, except at the 80 elongated end recesses 19, the inner edges of which are near the edges of the leaves.

The support 20 shown in Fig. 1 is similar to that shown in my copending application Serial No. 438,934, filed Jan. 21, 1921, 85 for loose-leaf binders and supports therefore, need not be here described in detail.

Within one hollow binder member 10, between the parallel spaced walls thereof, there is disposed a resilient clamp bar 22 90 (Fig. 4) provided with a transverse head-slot 23 open at its middle and having undercut opposite ends. Said bar is provided with locking openings 24 approximately registering with said orifices and having divergent 95 edges 25 forming slightly yieldable locking jaws.

Posts 27 passing through said perforations 7, openings 24 and orifices 12, 13, 14 and 15, are each provided at the lower end 100 with a retaining head 28 adapted to pass through the outer orifice 13 and to be held by engagement with the edge of the smaller inner orifice 15 of the hollow member 11. The upper end of each post is provided with a 105 pointed inserting or guiding head 30 adapted to pass through both the outer and the inner orifices of the hollow binder member 10.

A block 32 secured to one of said walls adjacent to said head-slot 23 is provided with a threaded hole longitudinal to the binder member; and a threaded key-shank 33 engaged in said hole is provided with a key receiving outer end, and at its inner end with cylindrical head in said slot engaging under the undercut portions thereof, and is adapted when rotated by a key, to 10 push upon the clamp bar to bring said converging jaws or edges 25 into locking engagement with said posts 27.

The operation of the device is very simple. The bound and locked loose-leaf book or 15 binder is placed on the support with its rear cover board resting upon the side bars 34 (Fig. 1), with the guide strips 36 engaging in the recesses 19 near the edges of the leaves, the forward edges of the leaves 20 or sheets being exposed and their inner edges 6 engaging against the stops 35, the keyhole of the binder member 10 being fully exposed.

A key is then inserted upon the squared 25 end 33 and the posts 27 are unlocked, whereupon the posts fall and are held by the heads 30 in the position indicated in dotted lines in Fig. 2, and the forward cover board 18 is removed and placed upon the supporting 30 strips 39 as in Fig. 1.

The leaves or sheets are then taken up one by one or in groups and deposited on the forward cover board 18 between the guide strips 40 with their inner edges against the 35 stops 37.

After all of the sheets have been placed in proper order on the forward cover board on the forward part of the support, the rear cover board is placed thereon, and the 40 posts which were pending therefrom as shown in the dotted lines of Fig. 2, are reversed and the head 30 is passed through the perforations 7, orifices 12 and 14 and the openings 24 until the head 28 engages 45 the edges of the orifice 15, after which the posts are locked in place. After the posts are thus locked in place, both side edges of the book are exposed thus permitting the hands to grasp the edges of the book for 50 removal.

The enlarged pointed heads 30, when passing through the perforations 7, serve to align the perforations and to guide the posts coaxially therethrough with a minimum of frictional contact.

Obviously, the operations above described and other features of the invention will be found useful in many operations other than those relating to accounting.

Having thus described my invention, I claim:

1. In combination, a locking binder member and a retaining binder member provided with orifices; posts passing through said orifices; and heads on both ends of said posts,

the heads at one end of both posts being of larger diameter than the posts and pointed.

2. In combination, a locking binder member and a retaining binder member provided with orifices; sheets between said members and having intra-marginal holes; posts passing through said orifices and holes; and heads on both ends of said posts, the heads at one end of both posts being of 75 larger diameter than the posts and pointed.

3. In combination, a locking binder member and a retaining binder member provided with orifices for posts; sheets between 80 said binder members and having holes spaced from the edges; posts smaller than said holes passing through said holes and orifices; heads on both ends of said posts and the heads at one end being adapted to pass through said holes and the orifices of the locking member and to be held against passage through the retaining member and the heads at the other end being adapted to be held against passage through the retaining member, whereby the posts are permanently retained in said orifices of the retainer member; and means carried by the locking member and having locking engagement with said posts.

4. In combination, a locking binder member; a retaining binder member comprising inner and outer spaced plates; the inner plate being provided with orifices; posts passing through said orifices; a clamp means associated with the locking binder member for locking it to said posts; and heads on both ends of said posts and adapted to engage both sides of said inner plate and to be held from passing through the orifices.

5. In combination, a locking binder member; a retaining binder member comprising inner and outer spaced plates provided with orifices; the orifices of the inner plate being smaller than those of the outer; posts passing through said orifices; a clamp means associated with the locking binder member for locking it to said posts; and heads on 110 said posts adapted to pass through the larger orifices and to be held from passing through the smaller orifices.

6. In combination, a locking binder member having orifices; a retaining binder member comprising inner and outer spaced plates provided with orifices; the orifices of the inner plate being smaller than those of the outer; posts passing through said orifices; a clamp means associated with the locking binder member for locking said posts; and heads on both ends of said posts and adapted to pass through the larger orifices and to be held from passing through the smaller orifices.

7. In combination, a pair of binder members provided with orifices for posts, the 130

- orifices of one binder member being smaller than those of the other; a clamp bar associated with the other binder member and provided with locking openings registering with said orifices and forming convergent locking jaws; posts passing through said openings and orifices; and heads on both ends of said posts and adapted to pass through the larger orifices and to be held from passing through the smaller orifices, whereby the posts are permanently retained in said smaller orifices. 35
5. In combination, a locking binder member and a retaining binder member provided with orifices; posts loosely passing through said orifices; and means engaging fixed parts of the binder member for retaining said posts in the retaining member. 40
6. In combination, a locking binder member and a retaining binder member provided with orifices; posts loosely passing through said orifices; and heads on both ends of said posts, the heads at both ends of both posts engaging fixed parts of the binder member for retaining the posts in the retaining member. 45
7. In combination, a locking binder member having orifices; a retaining binder member comprising inner and outer spaced plates provided with orifices; the orifices of the inner plate being smaller than those of the outer; posts passing through said orifices; a clamp means associated with the locking binder member for locking said posts; and heads on both ends of said posts and adapted to pass through the larger orifices and to be held from passing through the smaller orifices. 50
8. In combination, a locking binder member and a retaining binder member provided with orifices; posts of constant diameter loosely passing through all of said orifices; and heads on both ends of said posts for retaining the posts in the retaining member. 55
9. In combination, a pair of hollow binder members having parallel spaced walls provided with outer and inner registering orifices for the posts, the inner orifices of one binder member being smaller than the outer; a resilient clamp bar disposed in the other binder member and provided with locking openings approximately registering with said orifices and forming convergent locking jaws; posts passing through said openings and orifices; heads on both ends of said posts and adapted to pass through said orifices and openings except the smaller orifices, whereby the posts are permanently retained in said smaller orifices; the heads 60 on the ends most distant from the side wall carrying said smaller orifices being pointed; and means engaging said clamp bar and its enclosing member for moving said jaws into engagement with said posts. 65
10. In combination, a locking binder member having orifices; a retaining binder member comprising inner and outer spaced plates provided with orifices; the orifices of the inner plate being smaller than those of the outer; posts passing through said orifices; a clamp means associated with the locking binder member for locking said posts; and heads on both ends of said posts and adapted to pass through the larger orifices and to be held from passing through the smaller orifices. 70
11. In combination, a locking binder member and a retaining binder member provided with orifices; posts of constant diameter loosely passing through all of said orifices; and heads on both ends of said posts for retaining the posts in the retaining member. 75
12. In combination, a pair of hollow binder members having parallel spaced walls provided with outer and inner registering orifices for the posts, the inner orifices of one binder member being smaller than the outer; a resilient clamp bar disposed in the other binder member and provided with locking openings approximately registering with said orifices and forming convergent locking jaws; posts passing through said openings and orifices; heads on both ends of said posts and adapted to pass through said orifices and openings except the smaller orifices, whereby the posts are permanently retained in said smaller orifices; the heads 80 on the ends most distant from the side wall carrying said smaller orifices being pointed; and means engaging said clamp bar and its enclosing member for moving said jaws into engagement with said posts. 85

BERNARD R. DUTCHER.
